UNITED STATES PATENT OFFICE.

LOUIS LYMAN, OF CLEVELAND, OHIO.

DESIGN FOR A TOY BOAT.

Application filed December 10, 1926. Serial No. 20,008. Term of patent 3½ years.

To all whom it may concern:

Be it known that I, LOUIS LYMAN, a citizen of the United States, residing at Cleveland, in the county of Cuyahoga and State of Ohio, have invented a new, original, and ornamental Design for Toy Boats, of which the following is a specification, reference being had to the accompanying drawing, forming part thereof.

Fig. 2 is a plan view of the toy boat, and Fig. 3 is a bottom plan view of the toy boat.

I claim:

The ornamental design for a toy boat, as shown.

In testimony whereof I affix my signature.

LOUIS LYMAN.
